UNITED STATES PATENT OFFICE.

ARTHUR BATES, OF LEICESTER, ENGLAND, ASSIGNOR TO UNITED SHOE MACHINERY CORPORATION, OF PATERSON, NEW JERSEY, A CORPORATION OF NEW JERSEY.

UPPER-PULLING MACHINE.

Application filed September 1, 1920. Serial No. 407,531.

To all whom it may concern:

Be it known that I, ARTHUR BATES, a subject of the King of England, residing at Leicester, Leicestershire, England, have invented certain Improvements in Upper-Pulling Machines, of which the following description, in connection with the accompanying drawings, is a specification, like reference characters on the drawings indicating like parts in the several figures.

This invention relates to upper pulling machines for use in the manufacture of boots and shoes. In some of its aspects the invention has particular advantages as applied to pulling-over machines, which pull the upper at the toe and the opposite sides at one operation, and the invention is herein illustrated in its application to a power pulling-over machine of a well-known type characteristic features of which are shown and described in United States Letters Patent No. 1,029,387, granted on June 11, 1912, upon an application of R. F. McFeely. It is to be understood, however, that the invention in many of its aspects is not limited to machines of the illustrative type nor to any particular type of upper pulling machine.

Experience in the use of upper pulling machines has demonstrated that for some kinds of work advantages are involved in relaxing the force of the pull alternately with the stressing of the upper. For example, in United States Letters Patent No. 1,123,662, granted on January 5, 1915, upon an application of Charles F. Bennion, it was proposed in a pulling-over machine to relax the spring tension of the yielding upper pulling means at an intermediate stage in the upper pulling operation, the construction there shown having particularly in view a more effective shaping of the upper to the contour of the last in the co-operative action of the toe and side grippers. It is an object of this invention to provide, in a machine wherein the force of the pull is relaxed alternately with the stressing of the upper, a construction designed to render more effective and certain than heretofore the action of the upper pulling means upon the upper materials.

With the above and other objects in view, a feature of the invention consists in a novel organization of means for pulling and for relaxing the tension of an upper by relative movement between the last and means which

grips the margin of the upper. The invention is herein illustrated in its application to means for pulling an upper at the toe end of a last in an organization similar to that shown in said prior Bennion patent, the construction shown comprising means for imparting to the toe gripper a positive tension relaxing movement between successive pulling movements of the gripper effected yieldingly through the action of its up-draw spring. Insurance is thus afforded that for each shoe the pull on the upper shall be definitely relaxed, irrespective of the character of the upper and the last and of friction between the upper materials and the last. While the invention is thus illustrated in its application to means for pulling the upper at the toe end of a last in an organization designed to effect a "give and take" action between the toe gripper and the side grippers, it is to be understood that in many of its aspects the invention is not limited to means for pulling at the toe but has in contemplation advantages to be secured by alternate pulling and relaxing movements irrespective of the location at which the upper pulling force is applied.

The above and other features of the invention, including certain details of construction and combination of parts, will now be more particularly described with reference to the accompanying drawings and pointed out in the claims.

In the drawings:

Figure 1 is a view in side elevation, with parts in section, of a portion of a pulling-over machine in which the invention is embodied.

Fig. 2 is an enlarged detail view showing more clearly than Fig. 1 mechanism provided for imparting tension relaxing movement to the toe gripper, with the parts as they appear at a later stage in the cycle of operations than that illustrated in Fig. 1, and

Fig. 3 is a detail view of the toe gripper operating cam.

As in prior machines of the illustrative type, the upper pulling means comprises a toe gripper 2 and opposite side grippers 4 connected respectively to an intermediate up-draw lever 6 and to side up-draw levers 8 fulcrumed at 10 on the head of the machine. At their rear ends the levers 6 and 8 are in swiveled engagement with blocks 110

12 slidingly mounted on updraw tension rods 14 which carry updraw tension springs 16 acting between said blocks and tension nuts 18 on the upper ends of the rods. The rods 14 are secured in lugs 20 which project laterally from vertically movable cam slides 22 and 24 for imparting operative movements respectively to the toe gripper and the side grippers. The slide 24 has a roll 6 engaging in a cam groove 28 formed in the face of a cam wheel 30 fast on the usual cam shaft 32 of the machine, and the toe gripper slide 22 has a roll 34 engaging in a cam groove 36 formed in a toe gripper operating cam wheel 38 also fast on the shaft 32. It will be understood that upon the starting of the machine the slides 22 and 24 are moved downwardly by their cams and act through the springs 16 to close the several gripper jaws on the upper and then to impart upper pulling movement yieldingly to the toe and side grippers, effecting a relative separation between the swivel blocks 12 and the lugs 20 proportional to the compression of the springs 16. At the end of the upper pulling operation the machine comes automatically to a stop to permit inspection and adjustment of the upper, and upon the subsequent starting of the machine the remaining operations of the cycle, having to do with the overlaying and fastening of the upper, are effected as is usual in machines of the type illustrated.

As shown in Fig. 3, the toe gripper cam 38 is constructed substantially as shown in the prior Bennion patent, and upon the starting of the machine acts to impart a progressive yielding upper pulling movement to the toe gripper until the part *a* of the cam groove arrives in engagement with the roll 34. At this point a projection *b* of the cam begins to act on the roll to move it in the reverse direction, thereby raising the slide 22 to relax the force of the pull of the gripper. As the cam continues its movement the roll is again moved inwardly toward the axis of the cam to impart a second downward pulling movement to the slide 22 which acts through the spring 16 to move the toe gripper again yieldingly to pull the upper, the cam being shaped to move the slide to a slightly lower limit than in its first pulling movement. While the side gripper cam 30 may be shaped to operate the side grippers in any desired time relation to the toe gripper, it is contemplated that for the purpose of the give and take action of the illustrative machine this cam will be shaped, as in the machine of the prior Bennion patent, to impart pulling movement to the side grippers substantially at the time of the tension relaxing movement of the toe gripper. The toe gripper will thus operate to pull the upper lengthwise over the toe before the side grippers

begin to pull it transversely, and will operate again to subject the upper at the toe to the final tension after the side grippers have acted coordinate with the relaxing movement of the toe gripper to draw the upper to the last back of the toe. The first stopping position of the machine, at the end of the upper pulling operation, is indicated by the lower position of the roll 24 in Fig. 3. 70 75

In order to insure invariably for each shoe, irrespective of the character of the upper and the last end of the friction between the last and the upper materials, a movement of the toe gripper to relax the lengthwise tension of the upper, the cam slide 22 in the machine herein shown carries a pawl 40 which is arranged to engage ratchet teeth formed on a plate 42 secured on one side of the rear end portion of the toe gripper updraw lever 6, the pawl being held normally in engagement with the plate 42 by the action of a spring plunger 44 which is mounted in the pawl and engages the cam slide. In the relative movement of the cam slide and the updraw lever which occurs in consequence of resistance of the upper to the pulling movement of the gripper, the pawl rides idly over the ratchet teeth, and as soon as the part *b* of the cam starts to impart a reverse upward movement to the slide the pawl becomes immediately effective to transmit such movement positively to the gripper lever and thus to insure a definite reverse movement of the toe gripper for relaxing the tension of the upper. In the second downward movement of the slide the pawl is again permitted to ride idly over the ratchet teeth as may be required in imparting to the gripper the final yielding pull. The cam may, of course, be shaped to impart repeated tension relaxing movements to the slide, as suggested in said prior Bennion patent, in which case the pawl and ratchet mechanism would act repeatedly to impart positive relaxing movement to the gripper. 80 85 90 95 100 105 110 115

In order to free the updraw lever 6 from the action of the pawl 40 when the cam slide 22 is in its lowest position at the end of the final upper pulling operation, the pawl is provided with an arm 46 to engage the periphery of the cam wheel 38 and swing the pawl away from the ratchet teeth, as shown in Fig. 2. This leaves the toe gripper free to be manipulated by the operator in the customary manner for adjusting the upper on the last while the machine is at rest with the upper under tension, and also permits the toe gripper to spring upwardly out of the way as usual upon its release from the upper. Since in the first instance the slide 22 is not moved so far downwardly as in its final pulling movement, the pawl rests against the ratchet teeth in position to be 120 125 130

immediately effective in the reverse upward movement of the slide, and is not disconnected from the teeth until the slide is moved to its final lower limit. In order 5 that the reverse downward movement of the toe gripper and the compression of the gripper closing spring in the return of the parts to starting position may be effected by the action of the cam slide directly upon the 10 swivel block 12 and not through the pawl and the ratchet teeth, the plate 42 above the teeth is provided with a plane face 48 to be engaged by the pawl when the cam slide and the swivel block are in engagement with 15 each other, as they are after the gripper has released the upper.

Having described the invention, what I claim as new and desire to secure by Letters Patent of the United States is:

20 1. In an upper pulling machine, the combination with means for gripping an upper on a last, of power driven operating means constructed to insure in the pulling of every upper alternate tension applying and tension relaxing relative movements of said 25 upper gripping means and the last.

2. In an upper pulling machine, the combination with means for gripping an upper on a last, and operating mechanism for effecting relative movement of said gripping means and the last to pull the upper, of additional operating mechanism constructed to effect for each shoe irrespective of the character of the upper and the last a relative 35 movement of said gripping means and the last to relax the pull on the upper in time relation to the upper pulling operation.

3. In an upper pulling machine, the combination with means for gripping an upper on a last, and operating mechanism for effecting relative movement of said gripping means and the last to pull the upper, of additional operating mechanism automatically operative to effect a positive relative movement of said gripping means and the last to relax the pull on the upper in time relation to the upper pulling operation.

4. In an upper pulling machine, the combination with means for gripping an upper on a last, of power driven operating means for effecting automatically relative movements of said upper gripping means and the last in determinate order to pull the upper, then positively to relax the pull, and then again to pull the upper.

5. In an upper pulling machine, the combination with means for gripping an upper on a last, of power driven operating means automatically operative to effect in determinate order a series of relative movements of said gripping means and the last, first to pull the upper yieldingly, then positively to relax the pull, and then to subject the upper to a final pull.

6. In an upper pulling machine, the com-

bination with means for gripping an upper on a last, of means for effecting a yielding relative movement of said upper gripping means and the last to pull the upper, and a clutch device automatically operative in time relation to the pulling of the upper to effect a positive relative movement of the gripping means and the last to relax the force of the pull.

7. In an upper pulling machine, the combination with upper gripping means, of power driven operating means constructed to impart to said upper gripping means automatically in each cycle of operations of the machine an upper pulling movement, 75 then a positive reverse movement to relax the pull, and then another upper pulling movement.

8. In a machine of the class described, the combination with an upper engaging gripper, of power driven operating means constructed to move said gripper to pull the upper and for each shoe to impart also to the gripper, irrespective of the character of the upper and the last, a reverse movement 90 to relax the pull on the upper in time relation to the upper pulling movement.

9. In an upper pulling machine, the combination with an upper engaging gripper, of operating means constructed to impart to 95 said gripper in time relation an upper pulling movement, then a positive reverse movement to relax the force of the pull, and then another upper pulling movement beyond the limit of said first movement.

10. In an upper pulling machine, the combination with an upper engaging gripper, and operating means for moving said gripper to pull an upper, of additional means automatically operative in time relation to 105 the upper pulling movement of the gripper to move said gripper positively in the reverse direction to relax the pull on the upper.

11. In an upper pulling machine, the combination with an upper engaging gripper, of operating mechanism timed to impart to said gripper automatically in each cycle of operations of the machine separate movements to pull an upper yieldingly and a determinate movement in the reverse direction to relax the pull on the upper between said pulling movements.

12. In an upper pulling machine, the combination with an upper engaging gripper, 120 of a power driven operating member, a connection between said member and the gripper for moving the gripper to pull the upper, and an additional connection arranged to be operated by said member to impart a reverse movement to the gripper to relax the pull on the upper in time relation to its upper pulling movement.

13. In an upper pulling machine, the combination with an upper engaging grip- 130

per, of operating means comprising a member movable alternately in opposite directions for pulling the upper yieldingly and for then relaxing the pull on the upper 5 while the gripper remains in engagement with the upper, and a device automatically operative to effect a positive connection between said member and the gripper to move the gripper in the direction to relax the 10 pull while permitting the member to move relatively to the gripper in the upper pulling operation.

14. In an upper pulling machine, the combination with an upper engaging gripper, of a gripper operating member, means for moving said member alternately in opposite directions for pulling the upper and for relaxing the tension of the upper, a yielding connection between said member 20 and the gripper for imparting upper pulling movement to the gripper, and an additional connection between said member and the gripper for imparting tension relaxing movement positively to the gripper.

25 15. In an upper pulling machine, the combination with an upper engaging gripper, of a gripper operating member, a yielding connection between said member and the gripper for moving the gripper to pull 30 the upper, operating means for imparting upper pulling movement to said member and for then moving the member reversely to relax the force of the pull, and a device automatically operative to prevent relative 35 yield between said member and the gripper in the reverse movement of the member.

16. In an upper pulling machine, the combination with an upper engaging gripper, of a gripper operating member arranged for upper pulling movement and for alternate tension relaxing movement, and a clutch device automatically operative to effect a positive connection between said member and the gripper only in the tension 45 relaxing movement of the member.

17. In an upper pulling machine, the combination with an upper engaging gripper, of a gripper operating member, a yielding connection between said member and the 50 gripper for moving the gripper to pull the upper, operating means for imparting upper pulling movement to said member and for then moving the member reversely to relax the force of the pull, and a pawl and 55 ratchet mechanism for effecting a positive connection between said member and the gripper in the reverse movement of the member.

18. In an upper pulling machine, the 60 combination with an upper engaging gripper, of a gripper lever connected to the gripper, a cam slide yieldingly connected to said lever for imparting upper pulling movement to the gripper, cam means for 65 moving said slide in a direction to pull the

upper and for then imparting reverse movement to said slide to relax the tension of the upper, and a device automatically operative to prevent relative yield between said cam slide and the gripper lever in the reverse 70 movement of the slide.

19. In an upper pulling machine, the combination with an upper engaging gripper, of a gripper lever connected to the gripper, a cam slide yieldingly connected to 75 said lever for imparting upper pulling movement to the gripper, cam means for moving said slide in a direction to pull the upper and for then imparting reverse movement to said slide to relax the tension of 80 the upper, and a pawl and ratchet connection between said slide and the gripper lever arranged to permit the slide to be moved relatively to the lever in the upper pulling operation and to serve as a positive 85 connection between the slide and the lever in the tension relaxing operation.

20. In an upper pulling machine, the combination with an upper engaging gripper, of a member yieldingly connected to 90 said gripper for moving the gripper to pull the upper, means for imparting to said member separate upper pulling movements with an intervening reverse movement for relaxing the tension of the upper, 95 and a device automatically operative to effect a positive connection between said member and the gripper in the reverse movement of the member.

21. In an upper pulling machine, the 100 combination with an upper engaging gripper, of a gripper lever connected to the gripper, a cam slide yieldingly connected to said lever for moving the gripper to pull the upper, cam means constructed to 105 impart to said slide separate upper pulling movements with an intervening reverse movement for relaxing the tension of the upper, and mechanism comprising a pawl on said slide and ratchet teeth on the gripper lever for effecting a positive connection between the slide and the lever in said reverse movement of the slide.

22. In an upper pulling machine, the combination with an upper engaging gripper, 115 of a gripper operating member movable alternately in opposite directions for pulling the upper and for relaxing the tension of the upper, a device for effecting a positive connection between said member and the 120 gripper in the tension relaxing movement of the member, and means for rendering said device subsequently inoperative to permit said member and the gripper to resume their starting relation.

125 23. In an upper pulling machine, the combination with an upper engaging gripper, of a gripper operating member movable alternately in opposite directions for pulling the upper and for relaxing the tension of the 130

- upper, a clutch device for effecting a positive connection between said member and the gripper in the tension relaxing movement of the member, and mechanism automatically operative subsequently to cause the clutch device to break said positive connection. 5
24. In an upper pulling machine, the combination with an upper engaging gripper, of a gripper operating member, means for imparting separate upper pulling movements to said member with an intervening reverse movement to relax the tension of the upper, a pawl and ratchet device for effecting a positive connection between said member and the gripper in the reverse movement of the member, and a device automatically operative in the final pulling movement of said member to disconnect the pawl from the ratchet teeth. 10
25. In an upper pulling machine, the combination with an upper engaging gripper, of a gripper lever connected to said gripper, a cam slide yieldingly connected to said lever for moving the gripper to pull the upper, cam means for imparting to said slide movements alternately in opposite directions for pulling the upper and for relaxing the tension and a final movement to return the parts to starting position, a device automatically operative to effect a positive connection between said slide and the gripper lever in the tension relaxing movement of the slide, and means for rendering said device inoperative in the final return of the parts to starting position. 15
26. In an upper pulling machine, the combination with an upper engaging gripper, of a gripper lever connected to said gripper, a cam slide yieldingly connected to said lever for moving the gripper to pull the upper, cam means for imparting to said slide separate upper pulling movements with an intervening movement in the reverse direction for relaxing the tension of the upper, pawl and ratchet mechanism for effecting a positive connection between said slide and the gripper lever in the reverse movement of 20
- the slide, and means automatically operative in the final upper pulling movement of the slide to render said pawl and ratchet mechanism inoperative and thus to permit the gripper lever to assume its normal relation to the slide upon the release of the upper by the gripper. 25
27. In an upper pulling machine, the combination with an upper engaging gripper, of a gripper lever connected to said gripper, a cam slide yieldingly connected to said lever for moving the gripper to pull the upper, cam means for imparting successive upper pulling movements to said slide with an intervening movement in the reverse direction for relaxing the tension of the upper, mechanism comprising a pawl on said slide and ratchet teeth on the gripper lever for effecting a positive connection between said slide and the lever in the reverse movement of the slide, and an arm on the pawl arranged to be operated in the final upper pulling movement of the slide to disconnect the pawl from said ratchet teeth. 30
28. In a pulling-over machine, the combination with a toe gripper and opposite side grippers, and operating means for imparting upper pulling movements to the toe and side grippers in time relation, of mechanism automatically operative to impart to the toe gripper positive movement in the reverse direction to relax the pull on the upper in time relation to the upper pulling movement of the side grippers. 35
29. In a pulling-over machine, the combination with opposite side grippers and means for operating them to pull an upper transversely, of a toe gripper, and operating mechanism for imparting to said toe gripper separate upper pulling movements and an intervening positive movement in the reverse direction for relaxing the pull on the upper in time relation to the pulling movement of the side grippers. 40
- In testimony whereof I have signed my name to this specification.
- ARTHUR BATES.
